UNITED STATES PATENT OFFICE.

RACHEL SUDIAH, OF NEW YORK, N. Y., ASSIGNOR TO WILLIAM A. TOOKE, OF MONTREAL, QUEBEC, CANADA.

SOFT FOLD-OVER COLLAR.

1,320,183.

Specification of Letters Patent. Patented Oct. 28, 1919.

Application filed November 1, 1915. Serial No. 59,107.

To all whom it may concern:

Be it known that I, RACHEL SUDIAH, a citizen of the United States, residing in the city of New York, borough of Bronx, county 5 of Bronx, and State of New York, have invented certain new and useful Improvements in Soft Fold-Over Collars, of which the following is a specification.

This invention relates to improvements 10 in soft fold-over collars, and the object of the invention is to provide a collar of this character which will possess all the advantages of prior art devices, without embodying the disadvantages heretofore present in 15 such prior art devices.

As soft fold-over collars are generally very pliable and soft, when a necktie is adjusted between the folds thereof, the bow or knot of the necktie at the front of the collar 20 has a tendency to force the free ends of the fold apart at the front, and thus render the collar unsightly. It has been heretofore suggested, as a means for holding the ends of the fold-over portion together, to provide 25 button-holes at the corner of each folded-over portion, with which button-holes cooperates an ornamented pin, or the like, acting as a spacing member. This is the means which has been generally employed, 30 but the same is open to many disadvantages, chief among which is the fact that, when the bow or knot of the tie is large, said bow or knot forces the adjacent edges of the fold apart at that portion thereof intermediate 35 the upper edge of the collar and the lower edge thereof. As the upper edge is held together by well-known securing means, and the lower edge is also held together by the pin, the portion intermediate these points 40 is stretched apart by the necktie, and the stretching of this portion raises the lower edge of the collar and causes the same to bulge circumferentially around the front of the neck of the wearer. This is very unsightly, and in fact looks worse than the 45 collar would appear, if the pin were not used. Moreover, the button-holes in the fold-over portion of the collar, as well as the buttons and pins which ordinarily co- 50 operate therewith to hold the edges of the collar together, are more or less unsightly, and detract from the appearance of the collar, rather than enhance the same.

The present invention overcomes these disadvantages in that the means which main-

tains the front edges of the fold-over portion of the collar in proper relative position is concealed. Moreover, this concealed means is preferably associated with additional means, generally in the form of stiffening members, for rendering said adjacent edges relatively rigid whereby, when the collar is worn, the concealed means referred to serves to hold the edges together near the lower edge of the collar, and the customary means, such as a pin or clasp, operates to hold the collar together at its upper edge, while the stiffening members preclude the bulging or separating of the edges intermediate the top and bottom of the collar. A 65 collar embodying these features will lie perfectly flat and in proper shape, and will not be bulged vertically or circumferentially by a necktie positioned between the folds of the collar. 70

In the preferred practical form, the stiffening members referred to are whalebone or other relatively rigid material, which is inserted between the plies of the fold-over portion of the collar adjacent the free edges 75 thereof. On the concealed face of the fold-over portion of the collar, near one edge thereof, and adjacent or upon the stiffening member, is secured a button, while on the same face, and positioned adjacent or upon the other stiffening member, is secured a 80 loop. The lower portion of the neck-band of the collar is secured together by means of the usual collar-button passing through holes in the neck-band, and the upper edge 85 of the neck-band is also secured together by either a button and button-hole on the co-operating parts, or male and female clasp members. Obviously, the attaching of the 90 loop over the button of the fold-over portion will serve to maintain the edges of the collar in spaced relation, for the reason that, as both edges are rigid, the securing of said edges together at any point will maintain the edges together at all points. 95

Features of the invention, other than those specified, will be apparent from the herein-after detailed description taken in conjunction with the accompanying drawing.

In the accompanying drawing, I have 105 illustrated one practical embodiment of the present invention, but the construction shown therein is to be understood as illustrative, only, and not as defining the limits of the invention. 110

Figure 1 is a front elevation of a collar embodying the present invention, the parts of the collar being shown in the positions which they occupy when said collar is in place on the wearer, and

Fig. 2 is a fragmental view of the free ends of the collar separated and the normally folded-over portion folded up into the plane of the neck-band.

10 Referring to the drawings, A indicates a collar embodying, speaking generally, a neck-band B, and a fold-over portion C. The construction of the collar, *i. e.*, the general formation as to contour and shape 15 thereof, is that of any of the styles generally used.

Neck-band B is secured in place about the neck of the wearer by the usual rear collar-button, not shown, and by a front collar-20 button, over which are passed the button-holes b b' positioned near the free edges of the neck-band and adjacent the lower edge thereof. The circumference of the upper portion of the neck-band is maintained constant by coöperating attaching means, such 25 as a button and button-hole at the respective sides of the collar, or male and female clasp members, b^2 b^3 , respectively, correspondingly situated, which latter attaching 30 means I prefer to employ.

The adjacent edges at the front of the fold-over portion C are provided with stiffening members D D' positioned between the plies of material, and it is preferable 35 though not essential, to position these stiffening members as close as possible to the adjacent edges of said fold-over portion. On the concealed side of portion C, and near the lower edge thereof, are positioned a button 40 d and a coöperating loop d' , the button being positioned near one end of portion C, and the loop being positioned at the adjacent end thereof. The best results are obtained when button d is positioned on, or 45 closely adjacent to, the stiffening member D, and loop d' positioned on, or closely adjacent to, the stiffening member D'. The reason for this is that it is preferred to transmit the tension of loop d' as nearly directly as possible to the stiffening members D D', so that, instead of placing a strain 50 upon any particular point of the fold-over portion of the collar, such strain is distributed equally throughout the entire adjacent edges thereof.

The method of utilizing the present invention may be briefly set forth as follows.

The neck-band of the collar having been secured to the neck-band of the shirt of the 60 wearer by means including the button-holes b b' , the male and female clasp members b^2 b^3 are brought into engagement, and the necktie tied in place. This having been accomplished, loop d' is passed back of the 65 necktie, if the latter be a four-in-hand or

cravat, and said loop is placed in engagement with button d . The collar is now in proper position.

When adjusted as described, it will be apparent that the front of the collar is secured together at the upper portion thereof by clasp members b^2 b^3 and, as these members are positioned relatively close to the upper edge of the fold-over portion, the edges of said portion will be thus held 70 together near the upper edge of the collar, whereas the points of the fold-over portion will be held in proper relative position by loop d' . As the stiffening members extend along the adjacent edges of portion C, said edges will, throughout their entire extent, be held in proper, relative position. The means for accomplishing this result is moreover, entirely concealed, and the collar will be esthetic and pleasing in appearance, 80 and will more closely resemble a starched or laundered collar than it will the well-known soft fold-over collars now generally employed. It thus appears that marked advantages result from the coöperation between the securing means d d' and the stiffening members D. D'. 85

The form of attaching member described, *i. e.*, the loop and button, is that which it is preferred to employ, as this construction is 90 very cheap to manufacture. However, the present invention is not limited to the specific means illustrated, but is to be considered to be as broadly novel as is commensurate with the appended claims. 100

Having thus fully described the invention, what I claim as new, and desire to secure by Letters Patent, is:

1. A soft-collar comprising a band and fold-over top, of means for detachably connecting the ends of the said top together, said means consisting of a length of textile material folded back upon itself midway the length thereof to present a loop and having its ends stitched to the underside of one end of the fold-over top, and a button fastened to the underside of the other end of the fold-over top and adapted to be engaged by the loop, said means being concealed from view when the collar is in position on the neck of the wearer. 105

2. A soft collar comprising a band and a fold-over top, of a textile strap stitched to the underside of one end of the fold-over top, a button fastened to the underside 120 of the other end of the fold-over top and adapted to be engaged by the strap whereby the connecting means for both ends of the strap are concealed from view by the said fold-over top, and stiffeners located 125 within the said top in substantial juxtaposition with the points of the connection of the strap and button and immediately adjacent the vertical edges of the ends of the top. 130

3. A fold-collar having a band, a folded-over top, a button attached to the inner side of one end of the folded-over top, and a strap attached to the other end of the folded-over top provided with means engageable with said button.
  4. A fold-collar having a band, a folded-over top, a button attached to the inner side of one end of the folded-over top, and a strap stitched to the inner side of the other
- end of the top at a distance from its vertical end-edge corresponding substantially with the distance of the button from the neighboring vertical end-edge of the top, said strap being provided with means adapted to 15 engage said button.

In testimony whereof I have signed my name to this specification.

RACHEL SUDIAH.
